UNITED STATES PATENT OFFICE.

JOHN H. KEATING, OF ST. LOUIS, MISSOURI.

RAZOR-STROP SWIVEL.

SPECIFICATION forming part of Letters Patent No. 726,309, dated April 28, 1903.

Application filed June 27, 1902. Serial No. 113,406. (No model.)

To all whom it may concern:

Be it known that I, JOHN H. KEATING, a citizen of the United States, residing at St. Louis, in the State of Missouri, have invented 5 certain new and useful Improvements in Razor-Strop Swivels, of which the following is a full, clear, and exact specification.

My invention relates to that class of swivels for razor-strops designed for holding two 10 strops in such a way that the swivel may be inverted, thereby making both strops available for use on either side; and my invention has for its primary object to provide a simple, inexpensive, and durable double swivel 15 of this character having separate loops individual to the two strops.

With these ends in view my invention consists in certain features of novelty in the construction, combination, and arrangement of 20 parts by which the said objects and certain other objects hereinafter appearing are attained, all as fully described with reference to the accompanying drawings and more particularly pointed out in the claims.

25 In the said drawings, Figure 1 is a perspective view of my improved razor-strop swivel. Fig. 2 is a side elevation thereof. Fig. 3 is an edge view. Fig. 4 is a plan or end view; and Fig. 5 is an enlarged detail section on 30 the line 5 5, Fig. 2.

1 2 are two loops or links, which are provided with cross-bars 3 4, respectively, preferably formed integrally therewith and each serving for the support of one of the strops, 35 (not shown,) which may be looped there-around in the usual or any suitable way. The loops 1 2 are formed with two stems or pivots 5 6, respectively, on which are swiveled the eyes 7 8, by means of which the device may be suspended from a nail or other support, the ends of the pivots 5 6 being headed or upset, as shown at 9, after passing through suitable apertures in the eyes 7 8, so as to be capable of revolving freely independently of 45 said eyes. The loops 1 2 are arranged with their cross-bars 3 4 side by side and their eyes 7 8 turned in opposite directions, and the cross-bars are secured together by suitable attachments in such a manner as to firmly connect 50 the loops while holding their cross-bars a short distance apart to leave room for the looped

ends of the strops. In order that this form of attachment or connection between the cross-bars may be strong and durable and at the same time light, I prefer to form the same 55 separately from the loops 1 and 2, it being found in practice that this is the vulnerable point of the device, and casting such connections integrally with the loops does not afford sufficient strength. Hence I prefer to connect 60 the cross-bars together by means of the connection more clearly shown in Fig. 5, which consists of a short section of tubing 10, placed between the bars at each end, and a rod or rivet 11, passing through both bars and the 65 tube 10 with its ends upset, one of these devices being arranged at each end of the bars a sufficient distance apart to allow the strop-loops to pass between them.

By the means described it will be seen that 70 the two loops are held in parallel planes, with the connections 10 11 extending at right angles to them, and inasmuch as the connections may be composed of wrought metal the device is capable of withstanding the rough 75 handling which castings of this character are necessarily subjected to during the course of manufacture and marketing.

Having thus described my invention, what I claim as new therein, and desire to secure 80 by Letters Patent, is—

1. As a new and useful article of manufacture a razor-strop swivel comprising two loops for two strops respectively, arranged side by side and turned in opposite directions and 85 cross connections independent of said loops rigidly secured thereto for holding them together, substantially as set forth.

2. As a new and useful article of manufacture a razor-strop swivel comprising two loops 90 for two strops respectively each having a cross-bar, said cross-bars being arranged side by side with the loops turned in opposite directions and rigid connections independent of said cross-bars riveted thereto and securing 95 said cross-bars fixedly together, substantially as set forth.

3. As a new and useful article of manufacture a razor-strop swivel comprising two loops arranged side by side and turning in opposite 100 directions, rivets extending between said loops for securing them together and sections

of tubing arranged on said rivets respectively between said loops for holding the loops at a distance apart, substantially as set forth.

4. As a new and useful article of manufacture a razor-strop swivel comprising two loops each having means for supporting it, and a cross-bar arranged in the same plane as said means, said loops being arranged in two parallel planes at a distance apart and a rigid

connection between said loops securing them together; whereby the pull of the strop will be in direct line with the cross-bar, the loop and the said supporting means on the loop, substantially as set forth.

JOHN H. KEATING.
